UNITED STATES PATENT OFFICE.

NILS SJÖQUIST, OF STOCKHOLM, SWEDEN.

ADJUSTING-GEAR FOR ORDNANCE.

No. 928,207.

Specification of Letters Patent.

Patented June 1, 1909.

Application filed July 3, 1907. Serial No. 382,090.

To all whom it may concern:

Be it known that I, NILS SJÖQUIST, a subject of the King of Sweden, and resident of Stockholm, in the Kingdom of Sweden, have 5 invented new and useful Improvements in Adjusting-Gear for Ordnance, of which the following is a specification, reference being had to the drawings accompanying and forming a part hereof.

10 This invention relates to means for elevating and adjusting laterally of ordnance mounted in carriages.

The object of the invention is to make it possible to scour, by a rapid-firing machine- 15 gun or ordnance, a mark having a considerable extension in any direction whatever.

The invention consists, chiefly, in providing means for independently adjusting the sighting line of the ordnance so as to bear 20 first on the one and then on the other of the two ends of the mark and in providing means by which the mouth of the barrel can be reciprocated between the two terminal positions aimed at, *i. e.*, be moved in an oblique 25 direction with relation to the horizontal and vertical plane.

In the drawing, Figure 1 is a side-elevation and partial longitudinal section of an embodiment of my improved arrangement 30 for adjusting the line of sight. Fig. 2 is a rear view of the same arrangement. Fig. 3 is a plan-view thereof. Fig. 4 is a rear view of a part of the arrangement, the parts being shown in the positions for adjusting the gun 35 laterally.

Referring to the drawings, the barrel *a* of a gun or the like is mounted in the ordinary manner on trunnions *b* in the shanks *c* of a fork mounted in a cross-piece *d* (Figs. 1 and 40 2) in such a manner as to be able to turn about an axis at right angles to the axis of the trunnions, said crosspiece *d* being hung in the joints *e* so as to allow the barrel to be set to the inclination required. It is easily 45 seen that by this means the barrel may be turned vertically on the trunnions *b* and trained laterally by the fork *c* turning about its geometrical axis, so that the barrel is capable of swinging in any direction what- 50 soever.

Extending from the joints *e* are arms *f* carrying, at their lower ends, the ordinary training arc *g*. Extending downwardly from the arms *f* are projections *h* carrying the bearing 55 for the elevating worm *i* coöperating with a worm-wheel segment *k* attached to the gun-

carriage. The elevating worm can be easily disengaged, by any known arrangement, from the worm-wheel segment in order to enable the primary or coarser adjustment of the 60 ordnance by hand. Running on the primary training arc *g* is a sliding-piece *l* adjustable by a screw *m* or by hand, if the screw is disengaged. The rear part of the sliding-piece *l* forms a downwardly directed 65 semicircular arc *l'*. Mounted on the said arc is a sliding-piece *n* adapted to be moved along the arc by means of a screw *o*, or by hand, if the screw is disengaged. As shown in Figs. 2 and 4 the sliding-piece is formed in 70 correspondence to the arc *l'*, and formed integral with the said sliding-piece is an arc *o'* carrying a sliding-piece *p* or other suitable part adapted to be moved in one or the other direction by means of a screw *q* or by hand if 75 the screw is disengaged. Instead of the arc *o'* any other suitable guide such as a straight guide-bar or the like might be employed. Extending upwardly from the sliding-piece 80 *p* is a bearing *r* and journaled in the said bearing is a pin *s* firmly connected to the barrel and so located that the central axis of the pin passes through the center of the arc *l'*, at right angles to its plane, and through the point of intersection between the axis of the 85 trunnions *b* and a vertical plane through the axis of the barrel. Thus, the axis of the pin *s* may if desired coincide with the axis of the barrel.

From the aforesaid and the drawing it is 90 easily understood that, if the sliding-piece *n* is moved along the arc *l'* from its middle position toward one or the other end of the said arc, the arc *o'* will take up an oblique position in relation to the horizontal plane. 95 When the sliding-piece *p* is then reciprocated along the arc *o'*, the mouth of the barrel will obviously swing in an oblique direction corresponding to the angle which the arc *o'* forms with the horizontal plane. 100

The training device is used in the following manner. After the ordnance has been placed in front of the extended mark to be aimed at, the sliding-piece or movable part *p* is placed at the middle of the arc *o'*. The 105 sight-bar of the gun is adjusted for the distance to that end or wing of the mark which requires the highest elevation. The sliding-piece *n* may take up any position whatsoever in relation to the arc *l'*, due to the fact 110 that the axis of the pin *s* coincides with the geometrical axis of the arc *l'* as long as the

sliding-piece p is in its central position in relation to the arc o' , so that the position of the barrel is not changed, when the sliding-piece n is moved along the arc l' , provided the sliding-piece p is in its middle position. The coarser adjustment of the barrel toward the aforesaid end of the mark is performed by hand after disengaging the elevating worm i from the segment k and the screw m from the 10 training arc so that the barrel may be freely swung vertically on its trunnions b , b and laterally by the fork c turning in the cross-piece d , the adjustment being thereupon made more accurate by means of the elevating worm i and the screw m operating the sliding-piece l . When the elevating worm i is turned, the whole system (Fig. 1) swings about the axis of the joints e (only the worm-wheel segment k attached to the gun-carriage remains stationary). The sighting device is thereupon adjusted for the other end of the mark. During the sighting toward this end the elevating worm i as well as the sliding-piece l remain in their adjusted positions. The sighting is performed by moving the sliding-piece n along the arc l' and moving the sliding piece p along the arc o' so as to bring the sighting line to coincide with the said latter end of the mark. The 20 coarser adjustment is performed by hand, the more accurate adjustment being thereupon performed by means of the screws o and q . If the screw q is thereupon loosened, while all the other screws hereinbefore mentioned are kept tightened, the sliding-piece or movable part p can be reciprocated along the obliquely set arc o' in the manner hereinbefore described, the mouth of the barrel being thus caused to swing in an oblique 25 direction in relation to both the horizontal and the vertical plane, and the obliquely extending mark is thus battered along its whole length.

Having now described my invention, what

I claim as new and desire to secure by Letters Patent is:—

1. The combination of a barrel for guns, a carriage supporting the said barrel in such a manner as to allow it to swing vertically and laterally, a guide adjustably supported by the said carriage, said guide being adapted to be set in an oblique position corresponding to the oblique extension of the mark to be fired at, a part movable along the said guide, and a connection between the said movable part and the barrel causing the mouth of the barrel to swing in an oblique direction in relation the horizontal and the vertical plane, when the said part is reciprocated along the guide, substantially as and for the purpose set forth.

2. The combination of a barrel for guns, a carriage supporting the said barrel in such a manner as to allow it to swing vertically and laterally, a training arc attached to the said carriage, a second training arc adjustably supported by the former, a sliding-piece movable along the said latter training arc, a guide carried by the said sliding-piece, said guide being adapted to be set in an oblique position corresponding to the oblique extension of the mark to be fired, a part movable along the said guide, and a connection between the said movable part and the barrel causing the mouth of the barrel to swing in an oblique direction in relation to the horizontal and the vertical plane, when the said part is reciprocated along the guide, substantially as and for the purpose set forth.

In testimony whereof I have signed my name to this specification in the presence of two subscribing witnesses.

NILS SJÖQUIST.
